UNITED STATES PATENT OFFICE.

HARVEY S. PARK, OF HENDERSON, KENTUCKY.

ELECTRO-MAGNETIC CAR-BRAKE.

SPECIFICATION forming part of Letters Patent No. 296,349, dated April 8, 1884.

Application filed September 1, 1883. (No model.)

To all whom it may concern:

Be it known that I, HARVEY S. PARK, a citizen of the United States, residing at Henderson, in the county of Henderson and State of Kentucky, have invented certain new and useful Improvements in Electro-Magnetic Car-Brakes, of which the following is a specification.

My invention relates to improvements in those electro-magnetic car-brakes described in my co-pending application for Letters Patent, in which the dynamo or other source of electricity is placed upon the locomotive, with conductors connecting the same to each car of the train, means being provided by which an electrical current may be directed into such conductors to energize an electro magnet or magnets on one or more of the cars for the purpose of actuating a clutch-disk to wind a brake-chain and apply the brakes.

My present invention consists in the combination, within the frame of the braking apparatus, of two sets of electro-magnets, each having separate electrical communication with the generator, said electro-magnets being placed face to face, and having a clutch-disk placed between their faces and upon the shaft which carries the drum upon which the brake-chain is wound.

In order that my invention may be fully understood, I will proceed to describe it with reference to the accompanying drawings, in which—

Figure I represents an under side view of the clutch mechanism. Fig. II is a vertical section thereof on the line II II, Fig. I.

1 represents a metallic frame, fixed by any suitable means to the under side of the car, or to the car-truck. Journaled transversely in such frame is a shaft, 2, bearing at one end disks or flanges 3, between which a brake-chain, 4, is adapted to be wound on such shaft.

5 is a circular casing containing a number of electro-magnets, 6, and fixed to a hub, 7, which revolves freely on the shaft 2. The hub 7 is provided with circumferential rings 8, of brass or other conducting material, with which the brushes 9 are kept in constant contact for the purpose of conveying current to and from the conductors 10 10, which are connected, respectively, to the positive and negative poles of the generator through the medium of a suit-

able switch-board. The rings 8 have electrical connection with the coils of the electro-magnets 6.

A second casing, 11, is rigidly attached to the frame 1, and contains a second series of electro-magnets, 12, whose poles are placed face to face with those of the first casing, at a sufficient distance therefrom to allow of the rotation between the two casings of a disk, 13, of steel or soft iron, the hub 14 of which surrounds the shaft 2. A feather, 15, upon said shaft, occupying a groove on the inner face of the hub of the disk, allows longitudinal motion of the disk upon the shaft, while at the same time preventing its rotary motion thereon. The second series of electro-magnets, 12, are also connected by conductors 16 16 with the switch-board, under the control of the conductor or engineer, or both. A belt, 17, surrounds the periphery of casing 5, and transmits continuous motion thereto, during the movement of the train, from one of the car-axles. It will now be seen that if a current be thrown into the circuit 10 9 8 6, &c., the revolving magnets 6, being energized, will attract and retain the armature-disk 13, and such disk, being forced thereby to revolve, will carry with it shaft 2, wind up brake-chain 4, and thus apply the brakes. When the desired strength of brake application is reached, the current is diverted from the braking-circuit to the circuit 16 12 16, and the second series of electro-magnets, 12, thereby polarized, attracting and retaining in their turn the armature-disk 13, and thus locking the brakes to the desired position. When the brakes are to be taken off, the current is in turn diverted from the second series of electro-magnets, and the brakes are allowed to fall back or are thrown back by means of springs.

All matter shown and described but not claimed in the present application I have claimed in my before-mentioned co-pending application.

Having thus described my invention, the following is what I claim as new therein and desire to secure by Letters Patent:

1. In an electro-magnetic car-brake, in combination with a braking and a locking circuit and two separate sets of electro-magnets in said circuits, the armature-disk upon the braking-shaft, placed between the faces of such electro-magnets, and adapted to be operated thereby

to effect the application or locking of the brakes, substantially as set forth.

2. The combination, with the shaft 2, of the continuously-revolving series of electro-magnets 6 loose on said shaft, having hub 7, with conducting-rings and brushes and a clutch-disk placed opposite the faces of such electro-magnets for the purpose of applying the brakes.

3. The combination, with a revolving series

of magnets and a fixed series of magnets whose poles are opposite each other, of an armature-disk fixed to its shaft between said magnets by a spline and groove, and adapted to be attracted by either, as and for the purposes set forth.

HARVEY S. PARK.
